UNITED STATES PATENT OFFICE.

FREDERICK GOERTZ, OF NEWARK, NEW JERSEY, ASSIGNOR TO AUGUST GOERTZ & CO.,
A CORPORATION OF NEW JERSEY.

VANITY BOX.

Application filed September 26, 1922. Serial No. 590,573.

To all whom it may concern:

Be it known that I, FREDERICK GOERTZ, a citizen of the United States, residing at Newark, in the county of Essex and State 5 of New Jersey, have invented certain new and useful Improvements in Vanity Boxes; and I do hereby declare the following to be a full, clear, and exact description of the invention, such as will enable others skilled in 10 the art to which it appertains to make and use the same, reference being had to the accompanying drawings, and to characters of reference marked thereon, which form a part of this specification.

15 This invention relates, generally, to improvements in cases or boxes adapted to contain face-powders, cosmetics, and the like; and the present invention has reference, more particularly, to a novel and simply constructed vanity box or case, comprising a main body providing a compartment having means therein adapted to hold a rouge compact and puff, or the like, with which means is connected in a hinge-like or 20 pivoted manner, a frame carrying another member for the reception of a compact face-powder said latter compartment being adapted to be lowered into the main compartment of the box or case, and enclosed therein by 25 a closing lid or cover connected with said main compartment, when not in use, but when said lid or cover is opened, being adapted to be raised above the said main compartment, to enable the user to get at 30 the rouge compact and puff contained in said main compartment.

With the purposes of the invention hereinabove set forth, and other objects of the invention which will be apparent from the following detailed description of the same, the said invention consists, primarily, in the novel vanity box hereinafter set forth; and, the said invention consists, furthermore, in the novel arrangements and combinations as 45 well as of the construction of the said parts, all of which will be more fully described in the following specification, and then finally embodied in the clauses of the claims, which are appended to and which form an essential 50 part of the said specification.

The invention is clearly illustrated in the accompanying drawings, in which:—

Figure 1 is a top view and Figure 2 a front elevation of a vanity box or case made 55 according to and embodying the principles

of the present invention, the various members of the box being represented in their closed relation; and Figures 3 and 4 are a top view and a side elevation, respectively, of the vanity box or case, with the various 60 members of the same being represented in their opened-out relation.

Figure 5 is a longitudinal vertical sectional representation of the vanity box or case, with the various parts of the same also represented in their opened-out relation; and Figure 6 is a transverse vertical section of the same, said section being taken on line 6—6 in said Figure 5.

Figure 7 is a plan view of the rouge and 70 puff retaining means removed from the main body of the box or case; Figure 8 is a face view of the frame with which the movable face-powder compact-carrying member is used; and Figure 9 is a plan view of the 75 rouge puff used with the means represented in said Figure 7.

Similar characters of reference are employed in all of the said above described views, to indicate corresponding parts. 80

Referring now to the several figures of the drawings, the reference-character 1 indicates a complete vanity box, showing one embodiment of the principles of the present invention, the same in the present instance, and as 85 shown in the accompanying drawings, consisting of a main body-member or shell comprising a base 2, and circular side-wall 3 formed with a reduced receiving portion, as 4, for receiving the flange 6 of a lid or cover 5, suitably connected with the said side-wall 3 by means of any suitable hinge-connection, as 7. The said main body-member or shell and the said lid or cover may be made in any desired form of exterior shape or contour, to provide, when closed together, the desired ornamental effect and appearance, and, furthermore, at the proper locations, the side-wall 3 of the main body-member or shell and the flange 6 of the lid or cover are 90 respectively provided with any suitably formed catch-devices, as 8 and 9, adapted to be brought into locked registration with each other for maintaining the closed relation of the lid or cover with the said main body-member of the shell or box, as will be 95 clearly understood. Suitably disposed within the said lid or cover may be a mirror 10, the latter being maintained in its operative position within said lid or cover by means 100

105

110

115

of a suitable retaining ring 11, substantially as shown in Figures 3 and 5 of the drawings. Suitably disposed within the portion 12 of the said main body-member or shell, and held therein by frictional contact, or otherwise, as will be evident from an inspection of Figures 5 and 6 of the drawings, is the rouge-compact 13 and rouge-puff 14 receiving means, which consists, essentially, of a base-member or tray 15 having a surrounding side-wall 16, said side-wall being in turn surrounded by an outwardly extending horizontal flange 17, the marginal edge 18 of which corresponds to the inner contour of the side-wall 3 of the main body-member or shell, and with which side-wall the said edge 18 in the present case is in removable frictional retaining engagement. As shown more particularly from an inspection of Figures 3, 5, 6 and 7 of the drawings, the said outwardly extending horizontal flange 17 is formed with an annular depression, as 19, in the opposite sides of which are formed oppositely located perforations or holes, as 20. The reference-character 21 indicates a yoke-shaped frame, usually made of flat metal, said frame being provided with a centrally disposed receiving portion 22, and at its free ends, the said frame 21 being provided with outwardly extending pintles or journal-members 23, adapted to be inserted in the previously mentioned perforations or holes 20, for oscillatorily connecting said frame 21 with the flange 17 of the rouge-carrying means, the said yoke-shaped frame being of such configuration, so that when the various parts of the vanity box are brought into their closed relation, it will enter a portion of the previously mentioned depression 19, and will lie beneath the upper face of the flange 17, as will be clearly understood.

The shell or casing for the reception of the powder-compact 24 consists, essentially, of a base 25 and an upwardly extending side-wall 26, said base 25 being provided upon its lower end and at one side of the base, at or near the marginal edge, with a means of pivotal connection, as 27, usually in the form of two members, as indicated in Figure 5 which are brought into pivotal embracing relation with the receiving portion 22 of the yoke-shaped frame 21. The assemblage and means of oscillatory connection between the various parts of the vanity box, as hereinabove described, permits the powder-compact-containing element to be readily raised above the rouge-containing element, as clearly indicated in the several figures of the drawings; and, similarly, when the lid or cover of the vanity box is to be closed down upon the main shell of the box, said means of oscillatory connection permits the said powder-compact element to be lowered, so that it will enter the said main shell, and will rest directly above the rouge and rouge

puff containing means, in such a position that it will not project above the marginal edge of the side-wall of the main body-member or shell of the vanity-box, so that there will be no interference with the lid or cover, when closing the latter.

From the above description it will be noted that the powder and rouge carrier constitutes a unit complete in itself and independent from the main box or outer casing whereby it is easily removable from the latter, and consequently the unit may be made and sold separately as a refill for vanity boxes.

I am fully aware, that my present invention is capable of modifications, and that some changes may be made in the general arrangements and combinations of the various devices and parts, as well as in the details of the construction of the said parts, as set forth in the foregoing specification, and as defined in the clauses of the claims which are appended thereto. Hence, I do not limit my present invention to the exact arrangements and combinations of the said devices and parts, as described in the said specification, nor do I confine myself to the exact details of the construction of the said parts as illustrated in the accompanying drawings.

I claim:

1. A vanity box comprising a main shell, a lid or cover connected therewith, a second shell normally disposed within said main shell, and a movable connection between said main shell and said second shell for moving the latter shell from and above said main shell when the lid or cover is opened.

2. A vanity box comprising a main shell, a lid or cover connected therewith, a second shell normally disposed within said main shell, a yoke-shaped frame, a means of pivotal connection between said second shell and said frame, and a means of pivotal connection between said frame and said main shell for moving said second shell from and above said main shell when the lid or cover is opened.

3. A vanity box comprising a main shell, a lid or cover connected therewith, a rouge compact and rouge puff-containing means within said main shell, a second shell to hold face powder normally disposed within said main shell and above said rouge compact and rouge puff-containing means, and a movable connection between said rouge compact and rouge puff-containing means and said second shell for moving said latter shell from and above said main shell when the lid or cover is opened.

4. A vanity box comprising a main shell, a lid or cover connected therewith, a rouge compact and rouge puff-containing means within said main shell, a second shell to hold face powder normally disposed within said main shell and above said rouge compact

and rouge puff-containing means, a yoke-shaped frame, a means of pivotal connection between said second shell and said frame, and a means of pivotal connection between 5 said frame and the said rouge compact and rouge puff-containing means for moving said second shell from and above said main shell when the lid or cover is opened.

5. A vanity box comprising a main shell, 10 a lid or cover connected therewith, a rouge compact and rouge puff-containing means within said main shell, comprising a base, a surrounding wall, and a surrounding flange extending horizontally from said 15 wall, a second shell to hold face powder normally disposed within said main shell and above said surrounding flange, and a movable connection between said flange and said second shell for moving said latter shell 20 from and above said main shell when the lid or cover is opened.

6. A vanity box comprising a main shell, a lid or cover connected therewith, a rouge compact and rouge puff-containing means 25 within said main shell, comprising a base, a surrounding wall, and a surrounding flange extending horizontally from said wall, a second shell to hold face powder normally disposed within said main shell 30 and above said surrounding flange, a yoke-shaped frame, a means of pivotal connection between said second shell and said frame, and a means of pivotal connection between 35 said flange and said frame for moving said second shell from and above said main shell when the lid or cover is opened.

7. A vanity box comprising a main shell, a lid or cover connected therewith, a rouge compact and rouge puff-containing means 40 within said main shell, comprising a base, a surrounding wall, and a surrounding flange extending horizontally from said wall, said flange being formed with an annular depression, a second shell to hold face powder normally disposed within said main shell 45 and above said surrounding flange, a yoke-shaped frame receivable in said annular depression, a means of pivotal connection between said second shell and said frame, and a means for pivotal connection between said frame and the said annular depression of said flange for moving said second shell from and above said main shell when the lid or cover is opened.

55. 8. A vanity box comprising a main shell, a lid or cover connected therewith, a rouge compact and rouge puff-containing means within said main shell, comprising a base, a surrounding wall, and a surrounding 60 flange extending horizontally from said wall, said flange being formed with an annular depression, and oppositely located pintle-receiving perforations, a second shell to hold face powder normally disposed within 65 said main shell and above said surround-

ing flange, a yoke-shape frame receivable in said annular depression, pintle-members extending in opposite directions from the free end-portions of said frame, said pintle-members extending into said pintle-receiving perforations for oscillation therein and for moving said second shell from and above said main shell when the lid or cover is 70 opened.

9. In combination with a receiving element 75 adapted to contain a powder-compact or the like, a second receiving element, adapted to contain a rouge compact and a means of pivotal connection between said receiving elements, consisting of a yoke-shaped frame 80 pivotally connected with said first-mentioned element, and pintle-members extending laterally from the free end-portions of said frame, said pintle-members being pivotally connected with said second mentioned 85 element.

10. In combination with a receiving element adapted to contain a powder-compact, a second receiving element adapted to contain a rouge compact, said second element 90 comprising a base and an upwardly extending side-wall, a horizontal flange surrounding said side-wall, said flange being provided with an annular receiving depression, a yoke-shaped frame, a means of pivotal connection between said frame and said first-mentioned element, and a second means of pivotal connection between said frame and said second-mentioned element, said frame being adapted to enter into receiving registration with the annular depression of said 95 flange.

11. In combination with a receiving element adapted to contain a powder-compact, a second receiving element adapted to contain a rouge compact, said second element comprising a base and an upwardly extending side-wall, a horizontal flange surrounding said side-wall, said flange being provided with an annular receiving depression, 100 formed with oppositely located pintle-receiving perforations, a yoke-shaped frame pivotally connected with said first-mentioned element, and pintle-members extending laterally from the free end-portions of 105 said frame, said pintle-members being disposed in said pintle-receiving perforations, and said frame being adapted to enter into receiving registration with the annular depression of said flange.

12. In a vanity box, a tray having a depression formed therein to contain a cosmetic, a container movably secured to said tray whereby the cosmetic in the tray may be covered and uncovered by the movement 115 of said container.

13. A vanity box comprising an upper and lower part hinged to each other, a tray mounted in one of said parts, means to detachably secure said tray therein, said tray 120 130

- 4
- having an opening therein to contain rouge, a container pivotally secured to said tray.
14. A dismountable cosmetic carrier unit for vanity boxes, comprising a tray having a depression therein to contain rouge, a container for face powder normally covering said rouge tray, and means pivotally securing said powder container to said rouge tray whereby the former may be swung outwardly to uncover the latter.
15. A dismountable cosmetic carrier unit for vanity boxes, comprising a tray having a depression therein to contain rouge, a

15 container for face powder normally covering said rouge tray, and a yoke-frame having its ends fulcrumed on said rouge tray and to the central portion of which said powder container is pivotally connected, whereby the latter may be swung to laterally off-set relation to the former to uncover the 20 same.

In testimony, that I claim the invention set forth above I have hereunto set my hand this 22nd day of September, 1922.

FREDERICK GOERTZ.
